UNITED STATES PATENT OFFICE.

ORLANDO W. NORCROSS, OF WORCESTER, MASSACHUSETTS.

DESIGN FOR A SHELTER-SHED.

50,281.

Specification for Design.

Patented Feb. 6, 1917.

Application filed July 5, 1916. Serial No. 107,711. Term of patent 3½ years.

To all whom it may concern:

Be it known that I, ORLANDO W. NORCROSS, a citizen of the United States, residing at Worcester, in the county of Worcester and State of Massachusetts, have invented a new, original, and ornamental Design for a Shelter-Shed, of which the following is a specification; reference being had to the accompanying drawing, forming part of this specification, in which—

I claim:—

The ornamental design for a shelter shed as shown.

In testimony whereof I have hereunto affixed my signature.

ORLANDO W. NORCROSS.
